Theron P. Chase

by *Edmond A. Parker* ATTORNEY

UNITED STATES PATENT OFFICE.

THERON P. CHASE, OF DETROIT, MICHIGAN.

DESIGN FOR A RADIATOR FOR AN AUTOMOBILE.

50,266.

Specification for Design.

Patented Feb. 6, 1917.

Application filed November 11, 1916. Serial No. 130,912. Term of patent 14 years.

To all whom it may concern:

Be it known that I, **THERON P. CHASE**, a citizen of the United States, residing at Detroit, in the county of Wayne and State of Michigan, have invented a new, original, and ornamental Design for Radiators for Automobiles, of which the following is a specification, reference being had to the accompanying drawing, forming part thereof.

The figure is a perspective view of a radiator showing my new design.

I claim:

The ornamental design for a radiator for an automobile, as shown.

THERON P. CHASE.

Witnesses:

**R. B. PRESCOTT,
GEO. F. AUSTIN, Jr.**
